Specification for Design.

Patented Aug. 25, 1914.

Application filed January 29, 1914. Serial No. 815,312. Term of patent 7 years.

To all whom it may concern:

Be it known that I, ANDREW JOHN SANFORD, a citizen of the United States, residing at Newark, Ohio, have invented a new, original, and ornamental Design for a Bowl or Similar Article, of which the following is a specification, reference being had to the accompanying drawing, forming part thereof.

Figure 1 is a side elevation of a bowl or similar article embodying the design. Fig. 2 is a section on the plane 2—2, Fig. 1 looking in the direction of the arrows —2—. Fig. 3 is a section on the plane 3—3, Fig. 1 looking in the direction of the arrows —3—.

This design has for its chief characteristic

a wide, flaring bowl-shaped body having panels thereon converging downwardly and a flaring base joining the bowl having panels which converge upwardly, the panels of the bowl and the base being united by a collar as shown.

I claim:

The ornamental design for a bowl or similar article, substantially as shown and described.

ANDREW J. SANFORD.
